UNITED STATES PATENT OFFICE.

JAMES T. MORTENSON, OF KENOSHA, WISCONSIN, ASSIGNOR TO PETER B. NELSON, OF KENOSHA, WISCONSIN.

DOOR-LATCH.

1,115,005.

Specification of Letters Patent.

Patented Oct. 27, 1914.

Application filed May 4, 1914. Serial No. 836,321.

To all whom it may concern:

Be it known that I, JAMES T. MORTENSON, a citizen of the United States, and resident of Kenosha, in the county of Kenosha and State of Wisconsin, have invented certain new and useful Improvements in Door-Latches; and I do hereby declare that the following is a full, clear, and exact description thereof.

10 My invention has for its object to provide a simple, economical and effective door latch, the same being particularly designed for application to refrigerator doors or the like, wherein an approximately air-tight seal is desired between the door and its opening. The construction and arrangement of the latch is such that it is capable of self adjustment to compensate for swelling or shrinkage.

20 Primarily the invention embodies a reciprocative spring-opposed bolt under control of an oscillatory cam-carrying lever, which lever is provided with connections for manual manipulation upon either side of the door, it being understood that the bolt co-acts with a keeper or socket bracket carried by the door jamb and that the said bolt is suitably attached to the door.

With the above and other objects in view 30 the invention consists in certain peculiarities of construction and combination of parts as hereinafter set forth with reference to the accompanying drawings and subsequently claimed.

35 In the drawings Figure 1 represents a face view of a fragment of a door and its jamb equipped with a latch embodying the features of my invention, parts being broken away and in section to more clearly illustrate details of construction; Fig. 2, a sectional plan view of the latch and door, the section being indicated by line 2-2 of Fig. 1, and Fig. 3 an inverted detailed plan view of a portion of the bolt.

45 Referring by characters to the drawings, 1 represents a latch-plate that is secured to a door 2. The latch-plate is provided with projecting ears 3, 3', between which is pivoted one end of an actuating lever 4, the 50 opposite free end of the same being curved outwardly to offset from said plate having a vertically disposed hand-grip 4'. The lever is also provided with a cam-shoe 5 in-

termidiate of its ends, which cam is formed with an oblique working face 5' that terminates with a straight faced stop-lug 5''. The plate ear 3 is provided with a right-angle apertured web 3'', the aperture in which web is alined with the rectangular throat of a clip 6, the same being bolted or otherwise secured to the front edge of the plate. Shiftably mounted in the clip-throat is the rectangular neck portion 7 of a plunger-bolt, the same being provided with a tail stem 7' that is guided within the aperture of the ear-web 3'', the said bolt being disposed in parallel relation to the oscillatory lever. Hence it is manifest that, owing to engagement of the neck portion of the bolt with the rectangular throat of the clip, twisting of said bolt in its guides is eliminated. At the base of the bolt-neck the same is forwardly offset for the reception of an anti-friction roller 8 constituting a tappet for engagement with the working face of the lever-cam 5, it being understood that said cam is inclined from its high point in a backward direction toward the fulcrum point of the actuating lever. Surrounding the stem 7' of the bolt is a coiled spring 9, which coiled spring is interposed between the web 3'' and the end face of the squared neck portion of said bolt, whereby the latter is forced forward under spring tension. Forward movement of the bolt is limited by engagement of its tappet or roller with the cam and this engagement serves to force the inner edge of the actuating lever 4 against the face of the latch-plate, the said engagement being caused through the influence of the bolt-spring. The bolt movement is limited in the opposite direction by a shouldered head 7''' of said bolt that engages the adjacent face of the clip, the head being bifurcated for the reception of an anti-friction roller 8', as shown.

40 A keeper-bracket 10 is secured to the door-jamb 2', the same being provided with a socket 10' that is adapted to receive the bolt-head. One wall 10'' of the bracket-socket is inclined, as shown, and adapted to be engaged by the bolt-head roller 8', whereby the spring pressure exerted upon said bolt tends to force the door inwardly when the latter is in its closed position as shown 45 in Fig. 2. The inclined wall 10'' is, in turn,

merged into an oppositely inclined bolt-engaging or striking plate 10", which striking plate comes in contact with the bolt roller when the door is about to seat within 5 the jamb and thus forces said bolt back to load its spring preparatory to the said bolt being shot into its socket.

The latch-plate 1 is apertured for the reception of an inside latch-stem 11, the outer 10 end of which stem projects through the plate and is provided with a nose 11' that engages a socket formed in the lower face of the actuating lever 4. The inner end of the stem 11 projects through a guide-plate 12 15 that is secured to the inner face of the door and the extreme end of said stem is provided with an actuating knob 13.

As shown in the drawings, the door is illustrated in its closed position with the 20 bolt-head roller in engagement with the inclined face 10" of the socket and hence the spring pressure exerted upon said bolt will tend to force the door tightly against the seating faces of the jamb to hermetically 25 seal the same. The tappet roller 8 of the bolt at the same time exerts pressure upon the working face of the cam 5, whereby the actuating lever is jammed tightly against the outer face of the plate.

From the foregoing description it is obvious that, in order to open the door from the outside, a pull upon the hand-grip 4' of 30 said lever will cause the latter to swing outwardly upon its pivot and the inclined working face of the cam will thus, through its engagement with the tappet-roller 8, cause the bolt 4 to be retracted from the socket-bracket, whereby said bolt is freed and the door may be swung open. In this oscillatory movement of the lever it is obvious that the connected stem 11 will slide outwardly to compensate for the lever movement, there being sufficient play between the lever aperture and nose of said stem to permit 45 arc movement of the lever without cramping the sliding stem. It is also manifest that, in order to open the door from the inside, it is only necessary to push the stem 11 outwardly, whereby motion is transmitted to 50 the oscillatory lever, which motion, in turn, causes retraction of the bolt.

While I have shown and described the latch-stem 11 having a nose 11' engaging a socket formed in the lower face of the actuating lever 4, it is obvious that this latch-stem may be entirely disconnected from the lever with the nose 11' arranged to abut the

face of the same, whereby the lever is actuated from the inside of the door, in this construction the stem constituting a push-rod which will not be moved when the lever is actuated to release the latch. 60

I claim:

1. A lock comprising a spring-controlled reciprocative bolt, a socket-bracket for engagement therewith, a tappet carried by the bolt, a pivoted actuating lever associated with said bolt having a handle offset from the bolt in one direction, the said actuating lever being oscillatorily moved in a plane 70 common to movement of the bolt, a retracting cam carried by the lever for engagement with the bolt tappet, and an independent 75 slideable stem offset from the lever in the opposite direction from its handle having means engageable with the lever.

2. A lock comprising a plate, a spring-controlled reciprocative bolt in slideable union with the plate, a head in connection with the bolt having an anti-friction roller, 80 a socket-bracket for engagement with the anti-friction roller, the socket being provided with an inclined face that is merged into an oppositely inclined striking plate, a tappet roller extending from the bolt intermediate of its ends, a lever in pivotal union with the latch-plate, a cam having an inclined working face engageable with the tappet-roller, and means offset from the lever in opposite directions for actuating the 90 same from the inside or outside of the door.

3. A lock comprising a plate, a spring-controlled reciprocative bolt in slideable union with the plate, a head in connection with the bolt having an anti-friction roller, 95 a socket-bracket for engagement with the anti-friction roller, the socket being provided with an inclined face that is merged into an oppositely inclined striking plate, a tappet roller extending from the bolt intermediate of its ends, a lever in pivotal union with the latch-plate, a cam having an inclined working face engageable with the tappet-roller, and a slideable latch-stem positioned at a right angle to the lever engageable with the same. 100 105

In testimony that I claim the foregoing I have hereunto set my hand at Kenosha, in the county of Kenosha and State of Wisconsin, in the presence of two witnesses.

JAMES T. MORTENSON.
